UNITED STATES PATENT OFFICE.

DAVE RENCSOK, OF HUNTINGTON, WEST VIRGINIA.

PICTURE-FRAME HANGER.

Application filed October 30, 1922. Serial No. 597,924.

To all whom it may concern:

Be it known that I, DAVE RENCSOK, a citizen of the United States of America, and a resident of Huntington, county of Cabell, and State of West Virginia, have invented certain new and useful Improvements in Picture-Frame Hangers, of which the following is a full and clear specification.

10 The object of this invention is to provide a simple hanger device which may be anchored to the wall and ceiling in such manner as to be adapted to be positioned at any point along the wall and to be anchored in 15 place without the necessity of fastening to the wall hanger-strips or any other special supporting or anchoring devices, as more fully hereinafter set forth.

In the drawing—

20 Fig. 1 is a vertical sectional view of the device in use;

Fig. 2 is a detail perspective view of the device partly broken away.

The supporting member of the device consists of a tube 5 curved to arch form having a length about equal to the quadrant of the circle on which the arc is described, so that when this supporting tube is placed in the upper corner of the room, formed by 25 the side-wall and the ceiling, one end will abut against the ceiling and the other will abut against the wall, forming a sort of bracket extending from one to the other. The lower end of the tube is provided with 30 sharpened projections 6, which are adapted to be forced into the wall to permit the squared end of the tube to rest squarely against the flat face of the wall. The upper end of the tube is closed by a flat plate 7, which is adapted to rest squarely against the ceiling, this flat plate being provided with a hole 8 up through which is adapted 35 to slide the sharp point of a rod 9, which sharp point is adapted to enter the ceiling 40 when the rod is forcibly projected upwardly.

The sharpened rod 9 is enclosed in a tube and at its lower end is pivotally connected to the inwardly-extending end 10 of a lever 50 11 pivoted within the tube at 12, the body or main part of the lever being curved to correspond with the curvature of the tube and being adapted to swing into the tube through a slot in the top-side thereof. The 55 lower end of the lever 11 is provided with a depending hanger-wire 13, which depends

through a notch 14 in the lower side of the tube wall and is attached to a suitable hook 15 or other device for engagement with the picture-frame wire, so that, when the picture is hung on said hook 15, the weight thereof will be sustained by the lever 11.

It will be observed that when the device is placed in the position illustrated and described, lever 11 is swung upwardly to the position shown in dotted lines in Fig. 1, in which position the arm 10 draws down the spike 9, to bring its pointed end down to a point below the face of the top-plate 7. The sharpened points 6 are jammed into the wall. When the picture is hung upon the wire 13, the weight thereof will pull down the lever 11 and thus produce a forceful upthrust on the spike, sufficient to force its sharpened point into the ceiling far enough to anchor the upper end of the supporting tube and thus prevent it shifting laterally. Thus anchoring the upper end of the supporting bracket against lateral movement 75 serves to hold the lower end of the bracket-tube against the side-wall, with its sharpened projections embedded in the wall. In this way, as will be observed, the weight of the picture is utilized to anchor the supporting bracket-tube in position, thereby doing away with the necessity of driving nails in the wall or fastening hanger-strips along the wall, and whereby also I am enabled to hang a picture at any point along the length of the wall where the ceiling is available 80 as an abutment and anchoring point for the upper end of the support. It will be observed that the weight of the picture is brought close to the anchoring point of the lower end of the tube, thus rendering it 85 unnecessary to employ impractically-long entering points 6. It will be understood that the supporting tube may be ornamented and made into various shapes and figures with a view of making it attractive in appearance.

What I claim is:

1. A picture-hanging device consisting of a supporting member having one end adapted to abut against the ceiling and the other end adapted to abut against an adjacent point of the wall, this latter point being provided with sharpened projections adapted to embed themselves in the wall, a sharpened anchoring spike or point at the upper end of the supporting member, and means carried by the supporting member

for causing the weight of the picture to thrust said sharpened projection into the ceiling, for the purpose set forth.

2. A picture-hanging device consisting of 5 a supporting bracket having sharpened projections at its lower end to enter the wall and a movable sharpened projection at its upper end adapted to enter the ceiling, a lever on the bracket adapted to thrust the 10 movable projection into the ceiling, and means whereby a picture may be hung upon said lever.

3. A tubular curved bracket having a wall-entering projection or projections at its lower end and a movable anchoring-pin 15 at its upper end, a lever pivotally mounted within the tube and pivotally connected to said anchoring-pin, the arrangement being such that the weight of the picture applied to the free end of said lever will cause said pin to enter the ceiling.

In testimony whereof I hereunto affix my signature.

DAVE RENCSOK.
